(57) **CLAIM**

The ornamental design for an offset flashlight mount, as shown and described.

DESCRIPTION

FIG. 1 is a top isometric view of an offset flashlight mount showing my new design;

FIG. 2 is a bottom isometric view of the offset flashlight mount shown in FIG. 1;

FIG. 3 is a front view of the offset flashlight mount shown in FIG. 1;

FIG. 4 is a left side view of the offset flashlight mount shown in FIG. 1;

FIG. 5 is a right side view of the offset flashlight mount shown in FIG. 1;

FIG. 6 is a rear view of the offset flashlight mount shown in FIG. 1;

FIG. 7 is a top view of the offset flashlight mount shown in FIG. 1; and,

FIG. 8 is a bottom view of the offset flashlight mount shown in FIG. 1.

The broken lines represent portions of the offset flashlight mount that form no part of the claimed design.
